(57) **CLAIM**

The ornamental design for a printer, as shown and described.

DESCRIPTION

FIG. 1 is a front view of a first embodiment of a printer, showing the new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front view of a second embodiment of a printer, showing the new design;

FIG. 8 is a rear view thereof;

FIG. 9 is a right side view thereof;

FIG. 10 is a left side view thereof;

FIG. 11 is a top view thereof; and,

FIG. 12 is a bottom view thereof.

The dash-dot broken lines in the first embodiment represent the bounds of the claimed design that form no part of the claimed design. The evenly-spaced broken lines in the second embodiment depict portions of the printer that form no part of the claimed design.

1 Claim, 12 Drawing Sheets
